[57] **CLAIM**

The ornamental design for a flashing, as shown and described.

DESCRIPTION

FIG. 1 is a top, right side perspective view of a flashing showing the design;

FIG. 2 is an end view thereof, the broken-line disclosure of a roof structure being shown for illustration purposes only and forming no part of the claimed design;

FIG. 3 is a top plan view thereof;

FIG. 4 is a bottom view thereof;

FIG. 5 is a front elevational view thereof; and,

FIG. 6 is a rear elevational view thereof.

The flashing has been broken in the center to disclose indefinite length.
